INTERNAL COMBUSTION ENGINES IGNITION SYSTEMS

Filed June 17, 1960

FIG.1

FIG. 2

United States Patent Office Patented Feb. 19, 1963

Value of the present invention is to obtain a device for igniting the spark-plugs of an internal combustion engine, which device is synchronized with the rotation of the engine, and which device is capable of being connected in series with the primary winding of the ignition coil, so as to obtain a voltage which is proportional to the angular velocity of the engine, and which voltage is applied to the ignition coil.

Claims priority, application France June 22, 1959

2 Claims. (Cl. 315—205)

The present invention relates to ignition devices for internal combustion engines. More particularly it is an object of the invention to provide an improved ignition generator of the electronic type.

An ignition system according to the invention comprises a D.C. voltage source a delay line and the primary winding of a pulse transformer connected in series, a control device having thyratron control characteristics connected between the input of said line and said primary winding, the control electrode of which is connected to a pulse generator, the secondary winding of the pulse transformer being connected to an ignition distributor.

Preferably the control device is of the multi-junction semiconductor type.

The invention will be best understood from the following description and appended drawing given by way of a non limitative example.

In this drawing,

FIG. 1 illustrates one embodiment of an ignition generator according to the invention; and

FIG. 2 shows waveforms at different points of the circuit.

According to the embodiment shown in FIG. 1, a battery 1 is connected in series with an inductance coil 2, a rectifier diode 3, a delay line 4 and the primary winding 5 of a pulse transformer 6 having a secondary winding 7. A multi-junction semi-conductor device 8, which has the characteristics of a thyratron and comprises a control electrode 9, or another device having such characteristics, is connected in parallel across line 4 and primary winding 5. A semiconductor device of this type can withstand peak currents of about 150 a. and reverse voltages of about 40 v. A diode 10 is connected in parallel with semi-conductor device 8. The control electrode 9 is connected to one terminal of a circuit breaker 12 through an RC circuit comprising a resistor 13 and a capacitor 11 and having a suitable time constant for obtaining the pulses applied to electrode 9 through the breaker 12. The latter may be of either any conventional type used in motor car engine ignition systems, or a make and break device of the magnetic type, for example comprising a rotary magnet and a moving coil or coil ensemble, such as that disclosed in the French Patent 1,183,698.

The secondary winding 7 of pulse transformer 6 is connected to a distributor 15 of the ignition system. Distributor 15 is mechanically or otherwise tied to the engine 16 in order to operate in synchronism and in phase therewith.

For example in the FIG. 1, the engine 16 operates two gear-boxes 17 and 18, the gear-box 17 being connected between the engine 16 and the distributor 15 and the gear-box 18 between said gear-box 17 and the circuit-breaker 12 with convenient reduction or multiplication ratios. The distributor 15 has four contact-studs 151, 152, 153 and 154 respectively connected to the four spark-plugs (not shown) of the engine.

The operation of the system shown in FIG. 1 will be explained with reference to the diagrams illustrated in FIG. 2 and which show the voltages appearing at the main points of the circuit of FIG. 1, these voltages being

as follows: point O is the point of connection of the primary winding 5 of the pulse transformer 6 and the control electrode 9 of the multi-junction semiconductor device 8; point A is the point of connection of the control electrode 9 and the circuit-breaker 12; point B is the point of connection of the circuit-breaker 12 and the secondary winding 7 of the pulse transformer 6; point C is the point of connection of the secondary winding 7 and the distributor 15; point D is the point of connection of the distributor 15 and the spark-plugs.

Two points are also indicated on the secondary winding 7 of the pulse transformer 6, namely point 1 and point 2, which points are connected to the terminals of a battery 1.

The voltage at point O of the diagram FIG. 1 is shown at O in FIG. 2. D.C. source 1 having a constant voltage U, the voltages appearing at point O are alternately U or zero, according as the circuit-breaker 12 is closed or open. The gear-box 17 having a ratio of $\frac{1}{2}$ and the gear-box 18 having a ratio of $\frac{1}{4}$, during each period of time of two cycles of rotation of the engine, said distributor 15 rotates once over all the four contact-

10 studs 151 and 154 and said breaker 12 is four times closed and four times open. Battery 1 charges the condensers of the artificial line 5 to a potential $2U$, the potential across the terminals of this battery being U. Pulses A of alternating polarities are applied to the control electrode 9 of

15 the semi-conductor crystal 8 by breaker 12. Whenever a pulse of a suitable polarity is applied to electrode 9, element 8 becomes conductive and causes the capacitors of the artificial line 4 to discharge. The voltage at point B is shown at B in FIG. 2. Each time this occurs the voltage

20 at B, which was equal to $2U$, falls nearly instantaneously to zero, then will increase, in a semi-sinusoidal way, up to $2U$, to collapse again when the next pulse of the same polarity occurs. Line 4 also is a pulse shaping circuit and rectangular pulses occur at point C. Then voltage

25 is raised by transformer 6 and the secondary winding 7 ultimately delivers pulses of the shape shown at D. Diode 10 avoids the harmful effects of the reverse current in the semi-conductor thyratron 8. Transformer 6 may, according to a well-known technique, be pre-magnetized by 30 means of a permanent magnet.

Among the advantages presented by the electronic ignition device of the invention, the following may be noted:

Accurate determination of the ignition periods

Excellent operation of the ignition, even when the impedance or the spark plug is low.

It is to be understood that the invention is in no way limited to the embodiment described and illustrated, which has been given only by way of example.

What is claimed is:

40 1. An ignition system for internal combustion engine having spark-plugs, comprising in combination: means for generating a pulse waveform voltage having a controllable recurrent period; means controlled by the rotation of said engine for tying said recurrence period to the period of said rotation; a multi-junction semi-conductor switching device having an input for receiving said pulsed voltage and an output; a delay line device, a transformer having a primary and a secondary winding; said 45 delay line device and said primary winding being series connected to said output of said multi-junction semi-conductor switching device; a constant D.C. current voltage source for energizing said ignition system; a rectifying diode series connected between said constant D.C. voltage source and said delay line device, for preventing the discharge of said delay line in said source; an ignition rotating distributor having contact studs, means for connecting said studs to said spark-plugs, and means for tying the rotation of said distributor to the rotation of said engine.

50 2. An ignition system for internal combustion engine having spark-plugs, two terminal inputs, means for connecting said terminals to a D.C. constant voltage source, said system comprising in combination: across said terminals, a circuit-breaker, means controlled by said engine for operating said circuit-breaker in synchronism with the rotation of said engine for generating a crenel waveform voltage having a period tied to said rotation; deriving means having an input for receiving said crenel waveform voltage and an output, said deriving means comprising a 55 capacitor and a resistor connected in series across said circuit-breaker and having a junction point at said output

of the same deriving means; a control device having thyratronic control characteristics, having an input and an output; means for feeding to said input of said control device the pulsed voltages issued at said output of said deriving means; a delay line device having an input and an output, said input of said delay line device being connected to said output of said control device; a rectifier diode and an inductance coil series connected between one of said terminals and said delay line device for preventing the discharge of said delay line in said source; a pulse transformer having a primary and a secondary winding, said primary winding being series connected with said output of said delay line device and with the other of said terminals;

minals; a rectifier diode bridge connected with said delay line and said primary for clipping the negative pulse of said delay line; a rotating distributor connected to said secondary winding; means for tying the rotation of said distributor to the rotation of said engine and means for connecting said distributor to the spark-plug of said engine.
